UNITED STATES PATENT OFFICE.

W. G. WARD, OF SAVONA, NEW YORK.

IMPROVEMENT IN NAIL-HAMMERS.

Specification forming part of Letters Patent No. 56,838, dated July 31, 1866.

To all whom it may concern:

Be it known that I, W. G. WARD, of Savona, in the county of Steuben and State of New York, have invented a new and useful Improvement in Hammers; and I do hereby declare that the following is a full, clear, and exact description thereof, which will enable others skilled in the art to make and use the same, reference being had to the accompanying drawings, forming part of this specification, in which—

Figure 1 is a perspective view of a hammer with my improvement applied thereto, showing the manner it is used. Fig. 2 is a side elevation, a portion being in section. Fig. 3 is a face view of the hammer-head.

Similar letters of reference indicate like parts.

My invention consists in attaching to a hammer of the ordinary construction a spring-socket for receiving the nail whose head abuts against a solid block or piece, whereby a person is enabled to "stick," as it is called, the nail in the desired place, when it will be drawn out of the socket and the driving in of the nail may be proceeded with in the usual way.

A designates a hammer-head of the ordinary construction.

B is a spring, which is attached to the under side, or that nearest the handle, of the driving part of the hammer. It is so arranged that the outer end will bear against the side of the driving end of the hammer. It is secured to the hammer in any proper way. In the present instance a metallic block, b, is

bolted to the hammer, and to this it is secured. This metallic block b serves as a head-block for the nail to rest against, and is strong enough to bear the blow necessary to stick the nail.

A groove, c, is made in the hammer underneath the spring B, and into this the nail is partially pressed by the spring, so that there will be little likelihood of its dropping out. So soon as the nail is stuck the driving of it in may be performed by the hammer in the usual way.

My invention is simple, and can be readily applied to an ordinary hammer without in the least injuring the same for any purpose for which it may now be employed.

By using a hammer with my invention applied thereto a nail may often be stuck where it would be almost impossible to reach so as to hold the nail with one hand while driving it with the other.

With such a hammer nails may readily be driven by one-armed persons, as shown in Fig. 1 of the drawings.

What I claim as new, and desire to secure by Letters Patent, is—

Holding the nail by means of the groove in the hammer, in combination with the head-block and spring, when constructed to operate substantially as described; and for the purpose set forth.

W. G. WARD.
